Horace D. Stevens Inventor
By A. L. Ely Atty's

UNITED STATES PATENT OFFICE.

HORACE D. STEVENS, OF AKRON, OHIO, ASSIGNOR TO THE FIRESTONE TIRE AND RUBBER COMPANY, OF AKRON, OHIO, A CORPORATION OF OHIO.

GRINDER.

Application filed February 26, 1924. Serial No. 695,206.

This invention relates to grinding machines and especially to a machine for grinding to shape the opposite ends of articles such as rubber pedal pieces.

The chief objects of the invention are to provide means whereby more accurate work may be accomplished in much less time with little labor and at low cost. More particularly, the purposes of the invention are to provide largely automatic means for applying work to grinding rolls, automatic means for rotating the work relative to the rolls as the work-applying means is advanced into cooperative relation with the grinder rolls, and means whereby a plurality of work-applying means may be so advanced into or withdrawn from cooperative relation with the grinder that while an article, supported in one work-applying means, is being ground, a finished article can be removed from another work-applying means and an article-blank to be ground inserted therein in readiness for a grinding operation.

More specific objects are to provide a pair of work-applying means so connected that as one is swung into cooperative relation with the grinders, the other is swung out of such cooperation, to provide yielding means for swinging the work-applying means so that the work will be maintained against the grinders as the grinding proceeds, means being provided to limit the motion of the work-applying means so that the depth of the grinding may be predetermined, and to provide yieldably mounted means for engaging the work-applying means and rotating the work therein as the work-applying means is swung into cooperative relation with the tool.

Another object is to provide means for automatically positioning the work relatively to the grinder as the work-applying means is advanced into cooperative relation therewith.

Other objects will appear from the following detailed description in connection with the accompanying drawings in which my invention is illustrated in its preferred form, it being understood that I do not limit my invention to the specific embodiment thereof shown in the drawings.

Of the accompanying drawings:

Figure 1 is a front elevation of a machine

embodiment my invention and adapted for grinding rubber pedal pieces;

55

Figure 2 is a right elevation of the machine as shown in Figure 1;

Figure 3 is a section on line 3—3 of Figure 2;

Figure 4 is an enlarged section on line 4—4 of Figure 1;

Figure 5 is a detail section on line 5—5 of Figure 2;

Figure 6 is an enlarged section on line 6—6 of Figure 1; and

65

Figure 7 is an elevation of a rubber pedal piece, the ends of which have been ground to shape in the machine.

While I have shown in the drawings a machine primarily adapted to shape the ends of 70 rubber pedal pieces, it will be understood that my invention is capable of general application to machines for forming various articles of metal, fibre, rubber, etc.

In the drawings, 1 designates a table or 75 bench having an opening 2 in the top thereof, over which is mounted a base plate 3 having an opening 3^a therein, the plate 3 substantially covering the opening 2. Mounted on the plate 3, respectively forwardly and so rearwardly of the opening 3^a, are bearing brackets 4 and 5, and secured to the under side of the plate 3, forwardly and rearwardly of the opening 3^a, and projecting downwardly through the opening 2 in the 85 table 1 are the bearing brackets 6 and 7. Respectively mounted on brackets 4 and 5 are brackets 8 and 9 adapted respectively to form, with brackets 4 and 5, separable bearings 10 and 11 in which is journaled a 90 grinder drive shaft 12 having secured thereon a pulley 13 for driving the shaft 12, the pulley 13 being driven by a belt 14 trained over a pulley 15 on the shaft of a motor 16.

For mounting the shaft 12 in the bearings 95 10 and 11, sleeves 14, 14 (see Figure 4) are secured thereon by set screws 15, 15. Each sleeve 14 is threaded at either side of each bearing 10 or 11 and the shaft is longitudinally secured in the bearings by washers 100 16, 16, nuts 17, 17 and lock nuts 18, 18.

For adjustably mounting grinder or emery wheels 20, 20 to operate upon articles of different sizes, sleeves 14 preferably are formed of such length as to extend inwardly 105 from the bearings 10 or 11 toward the center

of the shaft. The emery wheels 20 are secured on the sleeves 14 by discs 21, 21 screw-threadedly mounted on the sleeves 14 and by nuts 22, 22 and lock nuts 23, 23 engaged on the sleeves 14, washers 24, 24 being interposed between the nuts 22 and the emery wheels 20. The emery wheels 20 may be formed integrally in the shape shown in the drawings, but preferably are formed of two discs 20^a and 20^b, each of which is adapted to be removed and replaced by a disc of different shape.

For advancing the work toward and from the emery wheels 20, there is provided work carrying arms 25, 25 secured on a rock shaft 26 journaled in bearings 27 and 28 formed respectively in bracket 8 and bracket 9. Since the work is to be yieldingly held against the emery wheels 20 to maintain it against the wheels as the grinding proceeds, I provide fluid pressure means for rocking the shaft 26. The fluid pressure means includes a double-acting piston 29 slidably mounted in a cylinder 30 which is mounted on bracket 9, the upper portion of the cylinder being slotted and the piston 29 adjacent the slot in the cylinder being formed with rack teeth 31 (see Figure 2), whereby a sector gear 32 secured on the shaft 26 is permitted to extend into the cylinder 30 and into engagement with the rack teeth 31. For admitting fluid pressure first to one side and then to the other of the piston 29, a pipe 33 is connected to the cylinder 30 adjacent one end and a pipe 33^a is connected to the cylinder 30 adjacent the other end, the pipes 33 and 33^a being connected to a suitable valve 34 to which is connected a fluid pressure supply pipe 35. A hand lever 36 is provided for operating the valve. It is desirable to damp the motion imparted to the work carrying arms by the fluid pressure and to this end there is provided a dash pot 37 pivotally mounted on the base plate 3, the piston of which dash pot is connected by a rod 38 to an arm 39 secured on the shaft 26. For limiting the motion of the rock shaft 26, an arm 40 is secured thereon and projects between two lugs 41, 41 secured on the bracket 8, bolts 42, 42 being adjustably secured to the lugs for engaging the arm 40 to limit its swing.

In the production of rubber pedal pieces it is necessary that the work be rotated as it is being ground. For this purpose the end of each arm 25 is formed with a separable bearing 25^a adapted removably to receive a rotary work carrying member 43 which, in this instance, is formed with a square work receiving aperture 44 adapted to receive a pedal piece, designated 45, which is square in cross-section. Each work carrying member may be driven by a gear 46 formed thereon.

Means are provided which are adapted to

drive gears 46 as the work carrying arms are advanced into cooperation with the emery wheels. These means comprise arms 47, 47 journaled on a rod 48 secured, as indicated at 48^a and 48^b respectively, in brackets 70 4 and 5. Each arm 47 is formed with a projection 49 extending between apertured lugs 50, 50 formed on the base plate 3. A spring 51 is secured to a plug 52 mounted in one lug 50, the spring 51 being secured to the 75 projection 49 and normally tending to urge the arm 47 upwardly, and a bolt 53 is adjustably secured in the other lug 50 to limit the upward motion of the arm 47. A gear 54 is so journaled on the end of each arm 80 47 as to be adapted to mesh with a gear 46 on a work carrying arm. For driving each gear 54 a sprocket 55 is secured thereto and a sprocket chain 56 is trained over the sprocket 55 and over a sprocket 57 secured 85 on a sleeve 58 journaled on the rod 48 between the arms 47, 47. The sleeve 58 is driven by a sprocket 59 over which is trained a sprocket chain 60 extending downwardly through openings 3^a and 2 and driven by a 90 sprocket 61 secured on a shaft 62 journaled in the brackets 6 and 7. The shaft 62 may be driven by a pulley 63 secured thereon. The gears 46 are to be driven slowly as compared with the emery wheels 20 and, accordingly, if pulley 63 is driven by the same source of power as the emery wheels, i. e., by motor 16, suitable speed reducing transmission is required. For this reason a belt 64 is trained over pulley 63 and over a small 95 pulley 65 rotatably mounted with a large pulley 66 in brackets, indicated at 67, secured on the table 1, and a belt 68 is trained over the large pulley 66 and over a small pulley 69 secured on the shaft of the 100 motor 16.

For withdrawing the grinder dust from the machine and conducting it from the room in which the machine is installed, a casing 70 is so mounted on the machine as 110 to enclose the grinder wheels, a suitable opening 71 being provided in the casing to permit the entrance and exit of the work carrying arms 25 and a second opening 72 being provided to clear the parts 49 and to 115 permit the passage of drive chain 60 therethrough. A duct 73 leads from the casing 70 to a suitable suction fan (not shown).

It is frequently essential, as when articles are being ground to a definite length between 120 spaced grinder wheels 20^a, that the articles be properly positioned in the work carrying arms so as to be carried in proper position to the wheels 20^a. In certain instances this may be effected by positively clamping each 125 article in position in the arms 25. For the production of articles, such as the pedal pieces 45, however, I provide automatic means for positioning articles supported in arms 25 as the latter are swung into coop- 130

erative relation with the grinders. The article positioning means comprises angle pieces or guides 74, 74, one on the casing 70 at each side of the opening 71 in line with the movement of each work supporting, apertured member 43 toward the emery wheels 20. Each guide 74 is formed with a slotted arm 75 adapted to be adjustably secured on the casing 70 so that the guides may overhang the opening 71. The other arm of each guide 74 is bent upwardly away from the opening 71 so as to force an article engaging therewith, as an arm 25 is swung inwardly, longitudinally in the aperture 44 of the work supporting member 43.

In operation, the emery wheels 20 are so adjusted on shaft 12 as to grind a pedal piece of the desired length and the guides 74 are adjusted to permit an article blank 20 to pass therebetween and to guide the same in proper relation to the emery wheels. Bolts 42 are also adjusted to limit the swing of the arms 25 so as to gage the depth of the grinding, and bolts 53 are adjusted so as to permit the arms 47 to be urged by springs 51 into such position as to mesh with gears 46 at the limit of swing of arms 25. Power is then supplied to the motor 16 whereby the emery wheels 20 are rapidly rotated and gears 54 are slowly rotated each in the same direction as the emery wheels. Assuming that the parts are in the position shown in Figure 1, an article-blank is inserted by the operator into the aperture 44 and the lever 36 is swung clockwise, thus admitting air pressure through the pipe 33^a into the right end of cylinder 30 and forcing piston 29 to the left whereby rock shaft 26 will be rocked clockwise, thus swinging the right work carrying arm 25 toward the emery wheels 20 and simultaneously swinging the left work carrying arm 25 away from the emery wheels. As the work is carried between the guides 74, if it be not already in proper position in the aperture 44, one or the other of the guides will contact with the end thereof and shift it into proper position so that it will be centered with relation to the emery wheels 20.

As the right work carrying arm 25 approaches a position in cooperative relation with the emery wheels 20, the gear 46 thereon automatically meshes with the right drive gear 54 and drives the work in a direction opposite to that of the emery wheels 20, the gear 54 receding slightly from the position in which it is mounted by the action of arm 47 urging projection 49 against spring 51 as the meshing is effected, the gears 46 and 54 being retained in mesh as the grinding proceeds by the yielding pressure of the spring.

Presently the work contacts with the emery wheels 20 and is maintained in such contact as the grinding proceeds by the fluid

pressure constantly being exerted on the piston 29. The depth of the grinding is determined by the position of bolt 42 which engages arm 40 and prevents further rocking of the shaft 26.

While the grinding operation is being performed, the operator removes a previously ground article from the left work carrying arm 25 and inserts an article blank into its aperture 44, as described above. At the completion of the grinding operation, the lever 36 is swung back to the position shown in Figure 1, thus carrying the article blank in the left arm 25 into cooperation with the emery wheels 20 and carrying the finished work in right arm 25 out of such cooperation, as will be understood.

Modifications may be resorted to without departing from the spirit or scope of the invention as claimed in the appended claims.

I claim:

1. A tool, a plurality of work carrying means relatively movable toward and from said tool, yielding means for simultaneously urging one work carrying means relatively toward said tool and urging another work carrying means relatively away from said tool, and means for limiting the relative motion toward said tool of each of said work carrying means.

2. A tool, work carrying arms oscillatable toward and from opposite sides of said tool, a rock shaft on which said arms are secured, and means operable to rock said shaft simultaneously to swing one arm toward said tool and to swing another arm away from said tool.

3. A tool, work carrying arms oscillatable toward and from opposite sides of said tool, a rock shaft on which said arms are secured, a gear secured on said shaft, a reciprocable rack meshed with said gear, and fluid pressure means for reciprocating said rack.

4. A tool, a work carrying arm oscillatable toward and from said tool, a rock shaft to which said arm is secured, a gear on said shaft, a slidable rack meshing with said gear, and fluid pressure means for sliding said rack.

5. A tool, work carrying means relatively movable toward and from said tool, a rotary work supporting member mounted on said means, a gear on said member, a gear yieldingly mounted adjacent said tool, and means for driving said last mentioned gear, said gears being adapted to mesh as the work carrying means is moved into cooperative relation with said tool.

6. A tool, a rotary work supporting member movable toward and from said tool, means on said member for rotating the same, means for driving said last mentioned means as said member is moved into cooperative relation with said tool, said driving means being mounted on an arm, and means for

yieldingly urging said arm to maintain said driving means in engagement with the work rotating means as the tool cuts into the work.

7. A tool, a rotary work supporting member movable toward and from said tool, a gear on said member for rotating the same, a drive gear mounted adjacent said tool, a pivoted arm on which said drive gear is mounted, a sprocket secured to said drive gear, a second sprocket mounted on the pivot of said arm, a chain trained over said sprockets, means for driving said second sprocket, and means permitting said arm to yield as the gear on said work supporting member is moved into mesh with said drive gear.

8. A tool, a work carrying member for loosely receiving the work and movable toward and from said tool, and means adjacent the path of movement of said member for engaging and positioning the work therein as said member is advanced toward said tool.

9. A tool comprising spaced elements for operating upon spaced portions of an object, means movable toward and from said tool for carrying said object into contact therewith, and means disposed adjacent the path of said last mentioned means for so

positioning the object in said carrying means as it is moved toward said tool that the object will be properly applied to the spaced elements of said tool.

10. A tool, means movable toward and from said tool for applying an object to the tool, said means having an object-receiving aperture, and means at either side of the path of said work applying means for shifting the object into proper position in said aperture.

11. A tool, means movable toward and from said tool for applying an object to the tool, said means having an object-receiving aperture, and adjustable means at either side of the path of said work applying means for shifting the object into proper position in said aperture.

12. A grinder comprising spaced abrasive wheels relatively adjustable on a shaft, a work carrying device movable toward and from said spaced wheels, and means adjacent either side of the path of said device for positioning work in said device, said means being relatively adjustable so that they may be secured in alignment with the spaced wheels.

HORACE D. STEVENS.
